UNITED STATES PATENT OFFICE

124,428

DESIGN FOR AN EVAPORATING APPARATUS

Martin J. Kermér, Buffalo, N. Y., assignor to Buffalo Foundry & Machine Co., Buffalo, N. Y., a corporation of New York

Application December 26, 1939, Serial No. 89,134

Term of patent 14 years

To all whom it may concern:

Be it known that I, Martin J. Kermér, a citizen of the United States, residing at Buffalo, in the county of Erie and State of New York, have invented a new, original, and ornamental Design for an Evaporating Apparatus, of which the following is a specification, reference being had to the accompanying drawings, forming part thereof.

In the accompanying drawings:

Fig. 1 is a perspective view of an evaporating apparatus, embodying my design viewed from one side thereof.

Fig. 2 is a perspective view similar to Fig. 1 viewed from the opposite side thereof.

Fig. 3 is a top plan view of the same.

Figs. 4 and 5 are front and rear elevational views, respectively, of the evaporating apparatus embodying this design.

Figs. 6 and 7 are elevational views taken from the opposite ends, respectively, of the apparatus embodying this design.

I claim:

The ornamental design for an evaporating apparatus, as shown.

MARTIN J. KERMER.
